UNITED STATES PATENT OFFICE

CHARLES HILAIRE HENRI RODANET, OF NEUILLY-SUR-SEINE, FRANCE

DESIGN FOR A CLOCK LAMP

Application filed November 27, 1931, Serial No. 41,889, and in France August 13, 1931. Term of patent 7 years.

To all whom it may concern:

Be it known that I, CHARLES HILAIRE HENRI RODANET, a citizen of the Republic of France, residing at 23 villa Madrid, Neuilly-sur-Seine, France, have invented a new, original, and ornamental Design for a Clock Lamp, of which the following is a specification reference being had therein to the accompanying drawing, forming a part thereof.

Fig. 1 is a perspective view looking to-

wards the front of a clock lamp showing my new design, and

Fig. 2 is a perspective view looking towards the rear of the same.

I claim:

The ornamental design for a clock lamp, substantially as shown.

In testimony whereof I affix my signature.

CHARLES HILAIRE HENRI RODANET.
